UNITED STATES PATENT OFFICE.

GARDNER EARL MACKENZIE, OF NEW ROCHELLE, NEW YORK.

TOY ROLLER COASTER.

Application filed March 28, 1922. Serial No. 547,400.

To all whom it may concern:

Be it known that I, GARDNER EARL MACKENZIE, a citizen of the United States, and a resident of New Rochelle, county of West-
5 chester, and State of New York, have invented certain new and useful Improvements in Toy Roller Coasters, of which the following is a specification.

My invention relates to toy roller coasters to be used by children and I aim primarily to produce a coaster, of the type adapted to run on a track, which can be held at the top of the incline until the children are seated in place and then released
10 15 so that there is no danger of the coaster starting with the children half on, and also to produce a coaster which will come to a gradual stop near the bottom end of the track.

20 In the accompanying drawings, which show an illustrative example of a coaster and track embodying my invention, Fig. I is a side view of the coaster; Fig. II is an end view thereof; Fig. III is a bottom view 25 of the coaster and Fig. IV is a section on line IV—IV of Fig. III. Fig. V is a plan view of a section of track to go at the top of the incline; Fig. VI is a side view of the track shown in Fig. V; Fig. VII is a plan 30 view of a central section of track; Fig. VIII is a side view of the track shown in Fig. VII; Fig. IX is a side view of a section of track to go at the bottom of the incline and Fig. X is a side view of the track shown
35 in Fig. IX.

Referring to the drawings the coaster comprises a pair of end boards 2 and 3, which carry wheels 4 and guide rolls 5. The wheels 4 rest on the top of the track and
40 the guide rolls 5 go inside the track. The coaster is provided with side boards 6 and a top 7 and a central brace 8. Attached to the central brace 8 is a spring bar 9 which carries the hook 10. A cord 11 runs from the free end of the spring bar 9 through an opening 12 near the top of the end board 2. The cord 11 is provided with a ring 13. The top section of track which is shown in Figs. V and VI is provided with the rails
45 50 14 and a central rail 15. The central rail 15 carries a stop 16. The track (which should be placed on a hillside) is so set up that the central rail 15 is at the extreme

upper end of the incline. When the car is put on the track at the upper end, hook 10 55 engages with stop 16 and the car stays in place. As soon as the riders are seated one of them pulls on the ring 13 which lifts the spring bar 9. This permits the hook 10 to pass over the stop 16 and the car starts 60 down hill. The central sections of track, of which there may be as many as desired, are shown in Fig. VII and consist of the rails 14 and the ties 17. Each section has a hook 18 at one end and a pin 19 at the 65 other end. Also each section has dowels 20 at one end and corresponding sockets 21 at the other end. By virtue of the dowels and sockets and the pins and hooks the sections of tracks may be firmly attached together. 70 At the bottom of the incline there are used sections of track such as the one shown in Figs. IX and X. These sections comprise the rails 14 and the auxiliary rails 22, which extend above the rails 14 sufficiently far so 75 that when the car strikes these sections of track the auxiliary rails 22 contact with the side boards 6 and lift the wheels 4 clear of rails 14. Of course the friction between the side boards 6 and the auxiliary rails 22 will 80 be relatively great and the car will quickly come to a stop.

Many modifications may be made in the details of this device without departing from the spirit of my invention.

What I claim is:

1. A track intended to be laid on an incline, a car adapted to run on the track having rollers and side members adjacent the rollers, the track being provided at a desired 90 point with auxiliary rails adapted to contact with said side members of the car to lift the car so that said rollers are clear of the track.

2. A track intended to be laid on an incline, a car adapted to run on the track having rollers and side members adjacent the rollers and having a trigger hook and means for operating the same, the track being provided with a stop member to co-operate with the trigger hook of the car and also being provided at the desired point with auxiliary rails adapted to contact with said side members of the car to lift the car so that said rollers are clear of the track. 105

GARDNER EARL MACKENZIE.
